STAMP VENDING AND APPLYING DEVICE

Thomas J. Mazzone, Minneapolis, Minn.

Application November 4, 1954, Serial No. 466,866

16 Claims. (Cl. 216—25)

My invention relates to improvements in postage stamp vending and applying devices.

An object of this invention is to provide novel means for applying moisture to a given area on an envelope.

Another object is to provide novel means for pressing a postage stamp onto a moistened area of an envelope.

Still another object of this invention is to provide novel means for feeding a strip of postage stamps to an envelope and for positioning the outermost stamp in the strip on a moistened area of said envelope.

Still another object of this invention is to provide novel means for severing a postage stamp from a strip of postage stamps.

Still another object of this invention is to move a novel envelope moistening device and a novel stamp pressure and severing device into alignment with any one of a plurality of rolls of strips of postage stamps to be fed to envelopes.

Still another object of this invention is to provide novel means for unwinding a strip of postage stamps from any one of a plurality of rolls of strips of postage stamps and feeding the same to envelope supporting and positioning means.

Still another object of this invention is to provide novel automatic means for holding an envelope moistening device retracted and other automatic means for releasing the same.

These and other objects of the invention will be apparent from the following description reference being had to the drawings.

To the above end, generally stated, the invention consists of the novel devices and combination of devices hereinafter described and defined in the claims.

In the accompanying drawings which illustrate the invention, like characters indicate like parts throughout the several views.

Referring to the drawings:

Fig. 1 is a vertical section taken on the irregular line 1—1 of Fig. 5;

Fig. 2 is a vertical section taken on the line 2—2 of Fig. 1, and also includes parts which would lie in front of the sectional view, Fig. 1;

Fig. 3 is an enlarged sectional detail taken through the center of the partial spur gear 109;

Fig. 4 is a horizontal section taken on the line 4—4 of Fig. 3;

Fig. 5 is a horizontal section taken on the line 5—5 of Fig. 1, and showing the internal parts in plan view;

Fig. 6 is a vertical section taken on the line 6—6 of Fig. 1;

Fig. 7 shows part of the mechanism of Fig. 6 in its re-65 volved position;

Fig. 8 shows the mechanism after having returned to its normal position;

Fig. 9 is a horizontal section taken on the line 9—9 of Fig. 1;

Fig. 10 is a vertical section taken on the line 10—10 of Fig. 9;

2

Fig. 11 shows a portion of the top view of the device; Fig. 12 is taken on the line 12—12 of Fig. 2; Fig. 13 is taken on the line 13—13 of Fig. 12; and Fig. 14 is an enlarged sectional detail taken on the line 14—14 of Fig. 5.

An external casing A, which is essentially box-like in structure, provides housing and support for the mechanism within. It consists of a top 15, a bottom 16, a right-hand side 17, a left-hand side 18, a back 19, and a front 10 20. A portion of the top 15 is integral with the right-hand side 17, forming an access door 21, which is hinged at 22 to the bottom member 16. The device rests upon four feet 23 which are fixed to the under surface of the bottom member 16 in such an arrangement as to provide adequate support.

The mechanisms within the casing A may be classified into two principal groups according to their functions: the stamp-applying unit B, and the stamp-dispensing units C and C'.

20 The function of the stamp-applying unit B is to afford a handle for manual operation of the device, to wit: the portion of the envelope to be stamped, to actuate unit C or C' and, after a stamp has been presented by unit C or C', to sever its perforated line, and to press it firmly 25 to the wet surface of the envelope.

The entire unit B is suspended by its top plate 24 from two angle bars 25 and 26, the end portions of which are equipped with rollers 27 which may move in the channel guides 28. The end portions of the guides 28 are rigidly 30 fixed to the casing members 19 and 20. By means of the rollers 27, the entire unit B may be moved in horizontal forward and rearward motion into three discreetly located positions: a forward position, a rearward position, and a neutral position. When in its forward position, the unit B may actuate the stamp-dispensing unit C; when 35 in its rearward position it may actuate the stamp-dispensing unit C', and when in its neutral position, it may actuate neither unit C nor unit C'. Thus, if units C and C' contain different kinds of stamps, the stamps may be selected at will by moving unit B into either its forward or its rearward position. When the device is not 40 in use, the unit B would normally be moved into its neutral position.

These three positions of unit B are located automatically by means of two stops 29 and 30 which are located, respectively, on the left-hand end portion of the angle bar 26, and on the right-hand end portion of angle bar 25. Fig. 14 shows an enlarged sectional detail view of stop 29 and its associated parts. It shows the portion

50 of plate 31 which slides over the surface of the top flange of channel 28, its other portion being rigidly fixed to the top flange of the end portion of angle bar 26. Rigidly fixed at right angles to the top of the portion of plate 31 which is shown in Fig. 14 is a short strap spring 32 which has a short pin 33 fixed to the underside of its extremity. The forward position of unit B has been reached when the pin 33 engages hole 34, which is located in the top flange of channel 28. The back side of the hole 34 is inclined as indicated at 35. This permits forcible backward movement of unit B, while the vertical front edge of hole 34, together with a buckling action of spring 32, will prevent further forward movement of unit B when the pin 33 is thus engaged in hole 34.

With the exception that the strap spring of stop 30 is extended in a direction opposing that of spring 32, the stop 30 is of identical construction to that of stop 29. The rearward position of unit B is reached when stop 30 engages hole 36, the forward side of which is inclined to permit forcible forward movement, only, out of engagement therewith.

The neutral position of unit B has been reached when

the stop 29 engages the depression 37 which is located in the top flange of channel 28, as shown in Fig. 14.

The stamp-applying unit B consists of two main parts, both of which are rigidly suspended from the underside of the top plate 24, which has already been described, these two main parts being a reservoir 38 and the stamp-applying mechanism 39. Their relative positions can best be seen in Fig. 2. The reservoir is essentially a vertically elongated box-like structure, the bottom member of which projects toward the front of the device and forms a letter stop 40. The front side of the reservoir begins to curve forward in its upper half and thereafter curves toward a horizontal plane with an ever-diminishing radius, forming the cam surface 41. In this cam surface 41 is an aperture 42 through which a sponge or other porous material 43 protrudes slightly, being held firmly in place by a spring 44 which is anchored to the underside of the top of the reservoir. The lower end of sponge 43 extends into the fluid 45, the level of which must lie below lower edge of aperture 42 to prevent seepage onto the floor of the device—the upper portions of the sponge 43 being saturated with fluid by capillary attraction.

The stamp-applying mechanism 39 consists of several moving parts whose main frame and base of resistance is an inverted U-shaped strap of metal or other hard material 46 which depends rigidly and transversely from the underside of top plate 24. The right-hand prong 47 and the left-hand prong 48 of frame 46 are extended forwardly at their lower end portions and at the extremities of these extensions they are joined together by a brace 49. Further rigidity is given to this frame 46 by rearward extensions 50, of the lower end portions of prongs 47 and 48, which become integrally joined to the right and left sides, respectively, of the reservoir 38.

The vertical flange of a short-horizontally-disposed angle bar 51 is rigidly fixed to the outer surface of the lower end portion of prong 48. Its horizontal flange is integral with the lower half of a telescoping tube 52, and forms a base of resistance for a compression spring 53, which is confined within the tube 52, and whose function is to keep the handle 54 in its uppermost position when not in use, the upper half of tube 52 being embedded in said handle.

The lower end portion of the upper half of the telescoping tube 52 is rigidly engaged in a hole in the horizontal flange of a short angle bar 51a, the vertical flange of which is rigidly attached to the left prong 57 of the handle member 55. Also embedded in the handle 52 is the upper end portion of a strap of metal 55 in the form of an inverted U. It is located directly above the frame 46 and its right-hand prong 56 and left-hand prong 57 extend downwardly on either side of the top plate 24 to slide over the outer surfaces of frame members 47 and 48 when the handle 54 is depressed. The lower end portions of the prongs 56 and 57 are extended horizontally to the front and rear to accommodate long, horizontal slots 78. A rod 58 which extends through these aligned slots 78, has enlarged end portions which lie on the outside surfaces of the prongs 56 and 57, preventing endwise movement of the rod 58. This rod 58 also extends through aligned and forwardly-convex, semicircular slots 59 in the side members of frame 46. At the radial centers of the slots 59, two pins 60 project in opposing alignment from the inside surfaces of the prongs 47 and 48 of frame 46, and form an axis about which the mechanism between said prongs may revolve. This mechanism between prongs 47 and 48 is labeled unit b in the drawings. It consists of a secondary frame 61, which is equipped on one end with an absorbent roller, and on its other end with a combination pressure plate and cutting edge for severing the stamp from its adjoining stamp and for pressing it to the envelope. The frame 61 consists of member 62, formed in the shape of an inverted U, and a smaller U-shaped member 63, the legs of which project upwardly and are integrally attached to the inside

surfaces of the two legs of member 62. The two legs of member 62 have outwardly extending flanges, and its top portion has upwardly extending flanges, so that all three sides of this member resemble channel bars. Rigidly affixed to the outside surfaces of the two legs of frame member 62 and vertically disposed between their flanges, are two long rectangular plates which extend downwardly beyond the legs of frame members 62. Plate 64 is on the left side, and plate 65 is on the right side. These plates 64 and 65 also have aligned holes which admit the passage through them of the rod 58, and between plate 64 and the left leg of the handle member 55 is a spacing collar 66 through which the rod 58 also passes.

The lower end portions of the plates 64 and 65 are equipped with long vertical slots in which the legs 67 of roller holder 68 are capable of sliding in longitudinal motion with respect to plates 64 and 65. The roller holder 68 is in the form of an inverted U which has aligned holes in the lower end portions of its legs to accommodate a shaft 69 which also passes through the roller 70. The roller 70 is thus confined between the legs of the roller holder 68 and can move freely in rotary motion about its shaft 69. It is made of rubber or other resilient material and has a porous surface. The left-hand end portion of the shaft 69 is extended beyond the left leg of the roller holder 68 for a reason which will appear later.

The legs 67 of the roller holder 68 are normally kept at the lower extremity of the slots in plates 64 and 65 by the action of a compression spring 71, one end of which is rigidly fastened to the under surface of the secondary frame member 63, and the other end of which is rigidly fastened to the upper surface of roller holder 68.

Located between the vertical flanges of the top surface of the secondary frame member 62 is a device for severing a stamp from an adjoining stamp at its perforated line and for pressing the stamp to the surface of the envelope. This device consists of an essentially flat lever 72 which is hinged to a fulcrum which is in the form of a rod 73, the ends of which are rigidly engaged in aligned holes in the vertical top flanges of secondary frame member 61. The larger portion of lever 72 extends left of its fulcrum and the end portion thereof is slightly curved downwardly with respect to the plane of the lever. The lever 72 also projects for a short distance to the right of its fulcrum and the end portion thereof is bent upward at right angles to the plane of the lever and the top edge of the flange thus formed constitutes a pressure edge 74 for separating a stamp from an adjoining stamp. The lever 72 is kept in an extended position from the secondary frame member 61 by the action of a spring 75 which is rigidly attached to the top of frame member 61. An extension of the top end portion of plate 65 bears against the under surface of the right-hand end of lever 72 forming a stop 76, which prevents the lever 72 from failing to clear the top of the frame 46. An extension of the upper end portion of the plate 64 similarly forms a stop 77 for the left-hand portion of lever 72, so that it cannot be depressed beyond a horizontal position.

Referring now in particular to Figs. 2, 6, 7 and 8, it may be seen that when the handle 54 is depressed, the various elements of unit B operate as follows. The rod 58 enters the semicircular slots 59 in frame members 47 and 48 by means of short vertical slots. These short entry slots have correspondingly aligned holes in the sides of secondary frame member 62 and in its side plates 64 and 65. As continued depression of the handle 54 takes place, the rod 58 follows the semicircular path of slots 59, its horizontal motion with respect to the prongs 56 and 57 of the handle member being provided for by the horizontal slots 78 in the end portions thereof. This semicircular motion of rod 58 causes unit b, through which it passes, to revolve about the axis provided by the pins 60 through an arc of approximately 180°. As the unit b is revolved, the roller 70 contacts the porous material 43, absorbs moisture therefrom, and is simultaneously pressed toward

the axis of unit *b* by the cam surface 41. As the roller 70 is pressed inwardly in this manner, the extended left end portion of the roller shaft 69 contacts the cam surface 79 of spring-loaded detent 80.

This detent 80 is in the form of a lever, pivoted at 81, to the outer surface of plate 64. The lower end portion of this lever is equipped with a hook 82 which is formed by an extension of cam surface 79. The upper end of the detent curves upwardly and rearwardly from the pivot point 81 and its end portion has a hole in which the end of a tension spring 83 is fastened. The other end of spring 83 is fastened to a small pin 84 which projects outwardly from the lower rear end portion of plate 64. A second small pin 85 projects from the outer surface of plate 64 just below the backwardly curved upper end portion of detent 80, forming a stop which limits the extent to which the detent 80 can be pulled back by spring 83, and also keeps said detent in position to be contacted by the roller shaft 69.

As the roller 70 continues its inward movement after its shaft has contacted the cam surface 79 of detent 80, it causes the cam surface 79 to slide backward, pushing the hooked end of detent 80 aside. However, when the extended shaft 69 reaches a point which is above the hook 82, the action of spring 83 causes the hook 82 to move quickly back into position and under the shaft 69 and to retain it in this inward position so that the roller 70 will not contact the envelope on its return trip. See Fig. 7.

When the handle 54 has been depressed to the point where the rod 58 has reached the lower extremities of the semicircular slots 59 in frame members 47 and 48, the pressure plate 72 is poised directly over the place where the letter is to be stamped. That portion of the envelope was damped when the roller 70 passed over it in the initial part of the depression of handle 54, and the timing with the action of a stamp dispensing unit C or C' (which will be described later) is such that, when unit *b* reaches this inverted position, a stamp is unrolled from one of said units and is placed directly over that portion of the envelope which is to be stamped. Continued pressure on the handle 54 therefore brings the pressure plate 72 into contact with the stamp. This continued downward movement, which must take place after the unit *b* has been inverted by the semicircular slots 59 is allowed by vertical slots 86 which extend downwardly from the lower extremities of the semicircular slots 59 in the frame members 47 and 48. This movement is also provided for by vertical slots 86 in the mid portions of plates 64 and 65, into which the pins 60 extend. When the pressure plate 72 is thus brought into contact with the stamp, the curved end portion contacts the back edge of the stamp first, fastening it tightly to the envelope. This action pulls the stamp taut, and as continued pressure is exerted on handle 54, the pressure edge 74 separates the stamp being applied from its adjoining stamp, and shortly thereafter the main body of the pressure plate 72 is pressed firmly against the stamp, affixing it tightly to the envelope.

After a stamp has been applied to an envelope in this manner and manual pressure is released from the handle 54, the handle is automatically returned to its upward position by the action of the compression spring 53. In this process, the unit *b* is revolved back through 180° into its original position. However, the extended portion of the roller shaft 69 is retained in an inward position by the hook 82 of the detent 80, so that the wet roller 70 will not pass over the stamp which has just been applied. When the unit *b* has nearly returned to its normal position, a small plate which projects outwardly from the surface of the detent 80 and at right angles to the plane thereof, contacts a short pin 88 which projects inwardly from the left prong 48 of frame member 46. This pushes the detent 80 backward, and releases the roller shaft 69 from the hook 82 of detent 80, putting said roller in position to moisten the next envelope (see Fig. 8), when the handle 54 is again depressed.

The stamp dispensing units C and C' are very similar in construction and function and have several parts in common, therefore, they shall be described together. Referring in particular to Figs. 1 and 5, it will be seen that the stamps 89 of both units C and C' are stored on a common shaft 90 which is supported at its center by a support 91 similar to a bearing, which is fastened to the floor of the device by screws. The end portions of shaft 90 are threaded to receive the stamp-retaining rings 92 in threaded engagement. The stamps are guided and unrolled by the mutual action of resilient rollers 93 and 94. Each roller 93 is rigidly fastened on its left-hand side to a spur gear 95, each of these combined gears 95 and rollers 94 is mounted on an individual bearing 96 and share a common shaft 97. The end portions of this shaft 96 are engaged in aligned holes in supports 98. These supports 98 are in the form of vertically disposed, essentially rectangular bars, from the bases of which two flanges project, said flanges being fastened to the bottom member 16 of the device by screws in a manner similar to that of the support 91, which is similar in appearance to the supports 98. See Fig. 1. Rollers 93 are situated directly below rollers 94 and each roller 93 is mounted on an individual bearing 99. The bearings 99 are mounted side by side on a common shaft 100, and the end portions of this shaft project through vertical guide slots 101 in the supports 98. Outwardly of each support 98, the shaft 100 is supported by compression springs 102; one end portion of each compression spring 102 being attached to a collar 103, through which the shaft 100 projects, and the other end portion being fastened to the top surface of a cube-like base of resistance 104 which, in turn, is integral with the bottom member 16 of the device. The purpose of spring 102 is to keep the stamps 89 snugly confined between the rollers 93 and the rollers 94, so that both the stamps 89 and the rollers 93 will be frictionally actuated by any movement of the rollers 94.

The force necessary to actuate these units C and C' is transmitted to the spur gears 95 by a system consisting of rack gear and partial spur gear combinations, a clutch system and a set of spur gears. This system can best be seen in Figs. 1 and 5. Two vertically disposed rack gears 105 and 106 are supported in parallel relation by forward and rearward extensions 105a and 106a of the right-hand prong 56 of the handle member 55. The rack gears 105 and 106 are positioned so that their teeth project to the right-hand side of the device. These gears are in the form of long, transversely rectangular bars having a discreet number of teeth which occupy what is roughly the middle third of the length of said bar, the rest of the bar being flat on its outer surface.

A long shaft 107 passes through holes in the vertical flanges of the angle bars 25 and 26, by which unit B is suspended, and the end portions of this shaft 107 are engaged in collars 108 which are rigidly fastened to the inside surfaces of the front and back casing members 29 and 19, respectively. Near the central portion of this shaft 107 is a partial spur gear 109 which is flanked on either side by friction plates 110 and 111, which are located to the front and rear, respectively, of the gear 109. These friction plates are so related to the gear 109 that they will be rotated only when the gear 109 moves in a counter-clockwise direction. The mechanism which thus relates the friction plates 110 and 111 to the gear 109 is as follows: A sleeve 112 fits over the shaft 107 in such a manner that it may be easily rotated about said shaft. The sleeve 112 has at its rear end portion a short annular flange 113. At its forward end portion is a slight annular groove which receives a removable clamp 114. Between the flange 113 and the clamp 114 two shorter sleeves 115 are confined and near the outer extremity of each sleeve 115 is a relatively large annular flange 116. The forward end portion of the forward sleeve 115 projects into the central hole in the friction plate 110 and said friction plate is rigidly fastened to the

outer surface of the forward flange 116. In a similar manner, the friction plate 111 is fastened to the outer surface of the rearward flange 116. The partial spur gear 109 is loosely confined between the flanges 116 and rotates on a bearing 117, part of which is integral therewith and which uses the outer surfaces of the sleeves 115 as a direct bearing surface. The central hole in the gear 109, through which the sleeves 115 project, is altered to afford three equally spaced recesses 118 which house the roller bearings 119. In Fig. 3 it may be seen that each of the recesses 118 tapers, in a clockwise direction, toward the outer surfaces of the sleeves 115, until it becomes tangent thereto. Also, each roller bearing 119 is forced into the tapered side of its recess 118 by small compression springs 120 which are confined between each roller bearing 119 and the untapered side of its recess 118. It may be seen that, when the gear 109 is rotated in a counter-clockwise direction, each roller bearing 119 will become tightly wedged between the tapered side of its recess 118 and the outer surfaces of the sleeve 115, thus forcing the sleeves 115 and 112 and, hence, the friction plates 110 and 111 to rotate also. However, when the gear 109 is rotated in a clockwise direction, the roller bearings 119 tend to roll freely in the larger sides of their recesses 118 so that only the gear 109 is rotated. Thus, when the handle 54 is depressed, and the teeth of a rack gear 105 or 106 engage those of the gear 109, the friction plates 110 and 111 are also rotated in a counter-clockwise direction; but when the rack gear 105 turns the gear 109 in a clockwise direction, as the rack gear 105 rises after the downward stroke, the friction plates are not rotated.

It may also be noted that the gear 109 has two teeth 109a, apart from its main body of teeth whose function it is to rest upon the flat surfaces of the rack gear 105, and thereby to keep said main body of teeth in a position to be engaged by the teeth of the rack gear 105.

Referring now to Fig. 5 in particular, it will be seen that the spur gear 109 and its friction plates 110 and 111 float on the shaft 107 between a rear compression spring 121 and a front compression spring 122. The vertical flange of angle bar 26 forms a base of resistance for the rear spring 121, and the vertical flange of angle bar 25 forms a base of resistance for the front spring 122.

On either side of the spur gear 109 and its friction plates 110 and 111 is a spur gear 123 and 124. The teeth of gear 123 mesh with those of the gear 95 of unit C' and the teeth of gear 124 mesh with those of the gear 95 of unit C. Each of the gears 123 and 124 is mounted on a bearing 125 which is press fitted to the outside surface of the end portion of a sleeve, which fits loosely over the shaft 107 and the springs 121 or 122. The sleeve 126, which supports the bearing 125 of gear 123, fits over the spring 121, and its outer end portion is rigidly engaged in a hole in a vertical support 128 having a flat horizontal, triangular base which is fastened to the bottom member 16 with screws. This sleeve 126 is long enough to allow the stamps from unit C' to pass between it and its gear 123. The sleeve 127 which supports the bearing 125 of gear 124 is shorter than sleeve 126. It fits over the spring 122 and its outer end portion is rigidly engaged in a vertical support 128 similar to support 128, the base of which is also fastened to the bottom member 16 with screws. A friction plate 130, which is the same diameter of friction plates 110 and 111 is rigidly fastened to the inside surface of gear 123, and a similar friction plate 131 is rigidly fastened to the inside surface of gear 124.

The springs 121 and 122 are adjusted so that they exert approximately equal force on the friction plates 110 and 111 of wheel 109 when the stamp-applying unit B is in its neutral position. Because of this, the friction plate 110 does not contact friction plate 13 nor does friction plate 111 contact friction plate 130. Also,

neither of the rack gears 105 and 106 will engage the spur gear 109 when unit B is in its neutral position.

However, when unit B is moved into its rearward position, the space in which spring 122 is confined is shortened and the space in which spring 121 is confined is lengthened. Thus spring 122 is under the greater compression, and it forces the gear 109 and its friction plates 110 and 111 to slide rearwardly along the shaft 107 until the friction plate 111 contacts the friction plate 130. Also, when unit B is in this rearward position, the gear 105 is placed in a position to engage the gear 109. Thus, when the handle 54 is depressed, the gear 105 engages and causes gear 109 to rotate on the shaft 107. The frictional engagement of gear 109 with gear 111 causes gear 111 to rotate also, and since its teeth are permanently engaged with those of gear 95 of unit C', it performs the function of unrolling a length of stamps.

Fig. 5 shows the unit B in its forward position and in an examination of this figure it will be seen that when unit B is in this position, the spring 121 forces the gear 109 and its friction plates 110 and 111 to slide along the shaft 107 until the friction plate 110 contacts the friction plate 131. This causes the gear 124 to rotate with the gear 109, and since the teeth of gear 124 are permanently meshed with those of the gear 95 of unit C, it performs the function of unrolling the stamps from unit C when actuated. It will also be seen that when unit B is in its forward position, the gear 106 engages the gear 109 when the handle 54 is depressed.

It is important that the relative spatial arrangements and sizes of the gears 105, 106, gear 109, semicircular slots 59 and slots 86 be such that the following operations are carried out in carefully timed sequence, when handle 54 is depressed:

1. The wet roller 70 passes over the area of the envelope which is to be stamped;
2. A stamp is delivered from either unit C or C' and is placed over the moistened area of the envelope;
3. Stamp is firmly affixed to the envelope by the pressure plate 72 and is severed from its adjoining stamp by the pressure edge 74.

The inside surface of the bottom member 16 is fashioned in such a manner as best to accommodate the forms and functions of the mechanisms which it supports. In referring to Fig. 1, it will be noted that that portion of the bottom member which lies under the working area of unit B and under the various sets of gears is thickened for greater support. Also, the portion of the bottom member 16, to which the supports 98, 128 and 129 are fastened, is in the form of a recumbent flange 132 which extends to the left of the device and is integrally connected with the rest of the bottom member at its right end portion, as indicated at 133. Referring now to Figs. 9 and 10, it will be seen that underneath the flange 132 is an adjustable letter stop 134. This letter stop 134 is in the form of a long bar 135 having two flanges 136 integrally connected to its end portions and extending to the right-hand thereof. These flanges 136 also extend downwardly on either side of the thickened portion of bottom member 16, using it as a guide. A shaft 137 extends between the upper end portions of flanges 136 and its end portions are journaled in holes therein. The front end portion of the shaft 137 is extended beyond the outside surface of the front flange 136, and terminates in a flat handle 138. A long flat member which is parallel to the shaft 137, and one edge of which is rigidly attached to that portion of the shaft which lies between the flanges 136, acts as a stop 139 when its free edge falls by the pull of gravity, into one of a plurality of grooves 140 in the portion of the bottom member 16 which lies under the recumbent flange 132. These grooves 140 are angular and have two sides—their right sides are vertical, and their left sides are at a small angle to the horizontal plane. Further movement of the letter stop 134 is prevented when the stop

member 139 contacts the vertical right side of a groove 140. This letter stop 134 may be adjusted by manually turning the handle 138 until the stop member 139 is free of the groove in which it has been engaged, and by manually moving it to the right or left until the stop member 139 becomes engaged in the desired groove 140.

The upper surface of the flange 132 of bottom member 16 is altered to form two stamp guides 141. These stamp guides 141 are located, in parallel relation to one another, to the left of the rollers 93 and in alignment with the rolls of stamps 89 of units C and C'. The right-hand end portions of the guides 141 take the form of incline planes 142 which rise above the upper surface of the flange 132. The upper surfaces of these incline planes 142 follow a line which leads from a point tangent to the upper surface of the rollers 93 downwardly at an oblique angle toward the left hand into a curved juncture with the bottom surface of transversely rectangular grooves 143 in the upper surface of the flange 132. The purpose of these guides 141 is to prevent the unrolled stamps from being damaged by slipping off the rollers 93, as well as to guide them into the correct position for application to the envelope. Further guidance is given to the unrolled stamp by the action of two strap springs 144 which tend to prevent the unrolled stamps from escaping from the grooves 143 of the stamp guides 141. These springs 144 are rigidly supported, in parallel relationship with one another, by a shaft 145, the end portions of which are rigidly engaged in aligned holes in the supports 128 and 129. Said aligned holes are set low enough in the supports 128 and 129 so that the springs 144 will not interfere with the action of the spur gear 109. The strap springs 144, as may be seen in Fig. 1, are in the form of clockwise-expanding spirals which follow a straight line obliquely downward into the grooves 143, where they form a curved juncture with their free end portions, which lie in a horizontal plane in the grooves 143.

When a stamp is being applied to an envelope, added pressure is applied to the free end portion of the spring 144 which is involved in the process and hence to the edge of the stamp which lies beneath it, by the action of a spiral strap spring 146. This spring 146 is rigidly mounted on a shaft 147. The end portions of this shaft 147 are rigidly engaged in aligned holes in two outwardly extending right angular flanges 148, which are formed from frontward and rearward extensions of the lower end portion of an oblique rearward and downward projection of the right-hand prong 56 of the handle member 55. The spring 146 thus mounted is, as seen in Fig. 1, in the form of a clockwise-expanding spiral which follows a straight line obliquely downward to a point directly below the shaft 147 and directly above the free end portion of one of the springs 144. From this point, the free end portion of the springs 146 turns abruptly upward, forming a small pressure point 149. It may be noted that the spring 146 is located in a position that permits it to apply pressure on the free end portion of the spring 144 which happens to be in use at the moment. This pressure tightly confines the stamp which adjoins the stamp which is being applied to the envelope. This action aids in breaking the perforated line which separates the two stamps.

While there are herein disclosed but a limited number of embodiments of the structure, process and product of the invention herein presented, it is possible to produce still other embodiments without departing from the inventive concept herein disclosed, and it is desired, therefore, that only such limitations be imposed on the appended claims as are stated herein, or required by the prior art.

What I claim is:

1. In a device of the class described, an envelope supporting and positioning means, a liquid holding material, an elongated structure intermediately pivoted to turn about a horizontal axis and having at one end a moisture

applying device and having at its other end a stamp pressure and severing device, and means for turning the structure to alternately bring the moisture applying device into contact with the liquid holding material and thereafter bring the same into a position to apply moisture to an envelope on the supporting and positioning means, the turning of the structure also successively brings the stamp pressure and severing device into contact with a stamp in a roll on moistened area of the envelope.

5 2. The structure defined in claim 1 in which the moisture applying device is spring projected, said structure further including a cam at the liquid holding material for retracting the moisture applying device, automatic means for holding the moisture applying device retracted, and other automatic means for releasing the same when in its position for applying moisture to the envelope.

10 3. The structure defined in claim 1 in which the stamp pressure and severing device is a lever acting pivoted plate having a cutting edge and a spring yieldingly holding the 15 plate pressed outwardly, normally the plate is outwardly inclined and its free end portion is in a plane parallel to the pivot of said plate.

20 4. The structure defined in claim 1 further including a mount for a strip of stamps wound in a roll, and means for unwinding the strip of stamps from the roll and feeding the same onto the stamp supporting and positioning means.

25 5. The structure defined in claim 1 further including a mount for a strip of stamps wound in a roll, a pair of friction rolls between which an unwound portion of the strip of stamps extends, one of the rolls being yieldingly pressed toward the other roll, and means for intermittently driving the other roll to feed the strip of stamps onto the stamp supporting and positioning means.

30 35 6. In a device of the class described, envelope supporting and positioning means, a liquid reservoir, a liquid absorbing material in the reservoir and extending into an aperture in the reservoir, an elongated structure pivoted to turn about a horizontal axis and having at one end a moisture applying roller and at its other end a stamp pressure and severing device, means for turning the structure to alternately bring the moisture applying roller into contact with the liquid holding material and thereafter bring the same into a position to apply the moisture to an envelope on the supporting and positioning means, the turning of the structure also successively brings the stamp pressure and severing device into contact with a stamp in a roll on the moistened area of the envelope.

40 45 50 7. The structure defined in claim 6 in which the moisture applying roller is spring projected and in which the reservoir has a cam for retracting the roller, automatic means for holding the roller retracted, and other automatic means for releasing the roller when in its position for applying moisture to the envelope.

55 8. In a device of the class described, a support, a depending U-shaped main frame including a transverse member, fixed to the support and a pair of laterally spaced side members, a handle having a pair of depending legs extending through the support and overlapping the outer sides of the side members of the main frame, a U-shaped secondary frame within the main frame including a transverse member and side members, pivots fixed to the side members of the main frame and extending into longitudinal slots in the side members of the secondary frame, each side member of the main frame having a slot including a transverse inner section, an intermediate semi-circular section and a longitudinal outer section, a pair of plates between the side members of the main and secondary frames, a rod extending through aligned holes in the legs, the plates and the side members of the secondary frame and the slots in the side members of the main frame, a stamp pressure and severing device pivoted to the transverse member of the secondary frame, a roller holder attached to the side

11

members of the secondary frame for a limited sliding movement longitudinally thereof, a spring yieldingly holding the roller holder pressed outwardly from the secondary frame, a moisture applying roller journaled on said holders, a coiled spring yieldingly holding the handle and its legs raised with the rod in the inner section of the slots in the side members of the main frame.

9. The structure defined in claim 8 in which the coiled spring is held in a tube comprising two telescopically connected sections, one of which is fixed to the handle and the other of which is fixed to the main frame.

10. The structure defined in claim 8 in which the support is a rectangular structure having rollers, and guides in which the rollers travel.

11. In a device of the class described, envelope supporting and positioning means, two mounts each for supporting a strip of stamps wound into a roll, a pair of friction rolls for each roll of stamps and between which rolls an unwound portion of said roll of stamps extends to be fed thereby onto the stamp supporting and positioning means, means for driving one of the rolls of each pair, and means for moving the stamp supporting and positioning means into alignment with either pair of friction rolls.

12. The structure defined in claim 11 in which the means for driving one of the rolls of each pair includes a pair of gears fixed on the inner sides of the driven rolls, a shaft and meshing with the first noted gears, a single gear mounted to turn about the shaft means for connecting single gear to either one of the last noted gears to drive the same, and means for driving the single gear.

13. The structure defined in claim 11 in which the means for driving one of the rolls of each pair includes a pair of gears fixed on the inner sides of the respective rolls, a shaft, a pair of gears loose on the shaft and meshing with the first noted gears, the last noted gears having on their inner side friction surfaces, a tube turnable in the shaft between the last noted gears, a double faced friction disk fixed on each end of the tube, a single gear through which the shaft extends, a one way clutch connecting the single gear to the tube, means for moving the tube friction disks and single gear axially on the shaft to bring one of the friction disks into contact with the friction surfaces on the adjacent last noted gear.

14. In a device of the class described, envelope supporting and positioning means, two mounts each for supporting a strip of stamps wound into a roll, a pair of

12

friction rolls for each roll of stamps and between which rolls an unwound portion of said roll of stamps extends to be fed thereby and onto the stamp supporting and positioning means, means for moving the stamp supporting and positioning means into alignment with either pair of friction rolls, a gear fixed to the inner side of one of the rolls of each pair, a shaft, a pair of gears loose on the shaft and meshing with the first noted gears, the last noted gears having on their opposing sides friction surfaces, a tube turnable on the shaft between the last noted gears, a double faced friction disk fixed on each end of the tube, a single gear through which the tube extends, a one way clutch connecting the single gear to the tube, means for turning the single gear, a pair of opposing coiled springs encircling the shaft and each holding one of the friction disks in contact with the adjacent surfaces of the single gear, and means for compressing either one of the springs to increase its tension and permit expansion of the other spring to decrease its tension, whereby the spring having its tension increased will clamp the opposite friction disk between the opposing friction surfaces of the single gear and the respective last noted gear and drive the same.

15. The structure defined in claim 14 in which the means for turning the single gear includes a handle operated rack gear meshing with the single gear.

16. The structure defined in claim 14 in which the means for operating the coiled springs includes a structure having side members engaged by the spring as bases of resistance, said structure having roller guides in which the rollers travel, the means for turning the single gear includes a plunger acting handle mounted on said structure and having a rack gear meshing with the single gear, said rack gear being free to slide endwise on the single gear, the stamp means for applying a stamp to an envelope on the stamp supporting and severing means being mounted on said structure.
